Fig. 2.

Des. 195,937

PAGE 3

Fig. 3.

Fig. 4.

FIG. 1 is a front perspective view of a hair dryer bonnet embodying my new design;

FIG. 2 is a front elevational view of the hair dryer bonnet shown in FIG. 1;

FIG. 3 is a bottom plan view of the hair dryer bonnet shown in FIG. 1; and

FIG. 4 is a top plan view of the hair dryer bonnet shown in FIG. 1.

I claim:

The ornamental design for a hair dryer bonnet or similar article, substantially as shown.
